US00D876719S

(12) **United States Design Patent** (10) **Patent No.:** **US D876,719 S**
Vermette et al. (45) **Date of Patent:** **** Feb. 25, 2020**

(54) **VAPE DEVICE**

(71) Applicant: **CANOPY GROWTH CORPORATION**, Smiths Falls (CA)

(72) Inventors: **Yan Vermette**, Ottawa (CA); **Andrew Stewart**, Ottawa (CA)

(73) Assignee: **CANOPY GROWTH CORPORATION**, Smiths Falls, Ontario (CA)

(**) Term: **15 Years**

(21) Appl. No.: **29/653,723**

(22) Filed: **Jun. 18, 2018**

(51) **LOC (12) Cl.** **27-02**

(52) **U.S. Cl.**

USPC **D27/162**

(58) **Field of Classification Search**

USPC D27/162, 100, 101, 163–165, 167, 172, D27/174, 175, 176, 183, 185–194; D24/110, 110.5; 128/202.21, 203.12; 131/273, 274, 191, 330, 329; D19/115, D19/123, 137

CPC A24F 47/002; A24F 47/006; A24F 47/008; A61M 15/00; A61M 15/06

(57) **CLAIM**

The ornamental design for a vape device, as shown and described.

DESCRIPTION

FIG. 1 is a rear elevational view of the vape device; FIG. 2 is a front perspective view of the vape device of FIG. 1;

FIG. 3 is a left side elevational view of the vape device of FIG. 1;

FIG. 4 is a right side elevational view of the vape device of FIG. 1;

FIG. 5 is a top plan view of the vape device of FIG. 1;

FIG. 6 is a front elevational view of the vape device of FIG. 1; and,

FIG. 7 is a bottom plan view of the vape device of FIG. 1.

1 Claim, 3 Drawing Sheets
